UNITED STATES PATENT OFFICE.

AUGUSTUS W. BOWERS AND CHARLES NEWTON PROUTY, OF SPENCER,
MASSACHUSETTS.

DOUBLE-WELT SHOE.

Application filed July 6, 1926. Serial No. 120,563.

This invention relates to the manufacture of shoes of the welt type. It has been customary to make a certain style of welt shoe with a so-called "reverse welt," the welt 5 being stitched to the edge of the shoe upper in a position exactly reversed from the usual procedure. Such a reverse welt is very difficult to attach smoothly and neatly to the outer sole, as it is necessary to bend the welt outward and upward around the toe, rather than outward and downward, as is the usual and much more convenient procedure.

It is the general object of our invention to provide a construction in which the ornamental effect and other advantages of a reverse welt are attained, while avoiding the disadvantages above indicated.

To the attainment of this object, we preferably provide a two-piece welt comprising 20 a welt strip directly secured to the edge of the upper and an outer welt preferably stitched both to the welt strip and also to the shoe upper. This outer welt is formed and positioned similarly to the usual welt and may be secured to the outer sole 25 by bending the welt outward and downward, as in the ordinary welt shoe.

Our invention further relates to arrangements and combinations of parts which will 30 be hereinafter described and more particularly pointed out in the appended claims.

A preferred form of the invention is shown in the drawings in which

Fig. 1 is a transverse sectional elevation 35 of a partially completed shoe, showing the first step in the application of my invention;

Fig. 2 is a view similar to Fig. 1 but showing the parts after the second step in 40 the application of the invention; and

Fig. 3 is a similar view but showing the parts assembled to an outer sole.

Referring to the drawings, the first step in the application of our invention consists 45 in attaching a welt strip 10 to the edge of an upper 11 by a row of stitching 12. The welt strip 10 is preferably bevelled or reduced in thickness along its upper edge and the stitches 12 are inserted near the upper edge of the strip 10 and somewhat removed from the lower edge of the upper 11.

The next step in the application of our invention involves the securing of an outer welt 14 to the welt strip 10 and to the upper 11 by a second row of stitches 15, as

shown in Fig. 2. The outer welt 14 may be provided with a groove or recess 16 to receive the stitches and form a fold line, as in the usual commercial welt, and may be otherwise identical with the usual practice. 60

After the welt strip 10 and the outer welt 14 have been secured to the edge of the upper, as indicated in Fig. 2, the lower edges of the parts are trimmed closely adjacent to the stitches 15, as indicated in Fig. 65 3, and the outer welt 14 is then bent outward and downward and is secured to the projecting edge portion of the outer sole 17 by stitches 18 in the usual manner.

In this manner, the outer sole 17 is very 70 firmly secured to the upper 11 and the welt strip 14 is also firmly secured to the upper, producing an appearance substantially identical with the reverse welt previously used.

Our improved two-piece construction provides a stronger and more durable article, as an extra row of stitching is used, and the lasting and sole attaching operations are very much simplified and may be performed 80 in the usual commercial manner, rather than requiring high grade special workmanship, as was necessary with the reverse welt previously used.

It will be understood that the usual lining 85 and insole are to be inserted and secured in any customary manner, as by extending the stitches 12 or 15 therethrough.

Having thus described our invention and the advantages thereof, we do not wish to 90 be limited to the details herein disclosed otherwise than as set forth in the claims, but what we claim is:—

1. A welt shoe comprising an outer sole, an upper, a welt strip secured adjacent 95 its upper edge to said upper, and an outer welt secured to said welt strip at a lower point and turned outward and downward therefrom to engage said outer sole.

2. A welt shoe comprising an outer sole, 100 an upper, a welt strip secured to said upper by one row of stitching, and an outer welt secured to said welt strip and to said upper by a second row of stitching, and turned outward and downward therefrom 105 about said second stitching to engage said outer sole.

3. A welt shoe comprising an outer sole, 110 an upper, a welt strip secured adjacent its upper edge to said upper, and an outer

welt secured to said welting strip and upper near the lower edges of said strip, upper and outer welt, and turned outward and downward from its point of attachment to engage said outer sole.

4. A welt shoe comprising an outer sole, an upper, a welting strip secured adjacent its upper edge to said upper by a row of stitching extending therethrough, and an outer welt secured to said welting strip and upper by a second row of stitching extend-

ing through said upper, said welting strip and said outer welt below said first stitching and adjacent the lower edges of said parts, said outer welt being turned outward and downward about the second row of stitching to engage said outer sole. ¹⁵

In testimony whereof we have hereunto affixed signatures.

AUGUSTUS W. BOWERS.
CHARLES N. PROUTY.
